UNITED STATES PATENT OFFICE.

BENJAMIN ADRIANCE AND AMOS CALLESON, OF BROOKLYN, NEW YORK, ASSIGNORS, BY DIRECT AND MESNE ASSIGNMENTS, TO AMERICAN CAN COMPANY, A CORPORATION OF NEW JERSEY.

SHEET-METAL BOX OR CAN.

SPECIFICATION forming part of Letters Patent No. 742,951, dated November 3, 1903.

Application filed March 24, 1903. Serial No. 149,346. (No model.)

To all whom it may concern:

Be it known that we, BENJAMIN ADRIANCE and AMOS CALLESON, citizens of the United States, residing in Brooklyn, in the county of Kings and State of New York, have invented certain new and useful Improvements in Sheet-Metal Boxes or Cans; and we do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates to improvements in the manufacture of sheet-metal boxes, cans, or other vessels, and it has reference particularly to the formation of the joint or seam between the body and head of such vessels.

Heretofore it has been customary to secure heads to the bodies of sheet-metal cans and other vessels by folding together seaming, flanges on the head and body into a seam having a plurality of folds or thicknesses; but such folded seams without solder have not in practice been found to be hermetically tight even when composed of five, six, eight, or more folds or thicknesses, and it has heretofore been proposed to make such interfolded

seams hermetically tight by various expedients—such, for example, as by thinning, stretching, and expanding the inner fold or wall of the seam against the outer folds or walls thereof, as illustrated in the Mendham, Griffin and Higgs patent, No. 675,603, or by forming a series of indentations or cross or longitudinal corrugations in or extending through the entire thickness of the seam and the several folds or walls thereof from one

side of the seam to the other, as shown, for example, in the Walter Thompson patents, Nos. 697,955, 697,956, 700,575, 700,576, 700,577, and 700,578; but in practical operation such methods are slow and expensive, require special tools and machines, and are or may be attended with danger of breaking or cracking the stock and other difficulties.

We have discovered and demonstrated by experiment, and herein our invention con-

sists, that such seams may be made hermetically tight by longitudinally grooving one side of the seam, while its opposite side is maintained and supported in its original plain smooth shape. By thus longitudinally grooving one side of the seam, preferably the outside, while its opposite side is supported and maintained in its original smooth shape all spaces between the several folds or walls of the seam, including the most minute or hair-like passages, are effectually closed up or obliterated, and the laminated or interposed surfaces of the several folds of the seam are brought into close and perfect contact and compacted together along the line of the longitudinal groove extending the length of the seam or around the can, thus producing an hermetically-tight seam or closure. The seam thereby produced and embodying our invention, it will thus be understood, consists of one or more plain smooth folds at one side of the seam or part-way through its thickness and, of one or more longitudinally-grooved folds at the opposite side of the seam or for the remainder of its thickness and that the seam as a whole is of materially less thickness along the line of its longitudinal groove than it is at other parts or adjacent to such groove. In practicing our invention one side of the seam, preferably the inside thereof, is supported and maintained in its original shape by a chuck or head which fits snugly inside the countersink of the can-head, and the groove is formed in the opposite side of the seam, preferably the outside, by a seaming-roller having a narrow annular rib or bead on its periphery.

In the accompanying drawings, forming a part of this specification, we have for convenience illustrated our invention as practiced with and applied to what is commonly known to those skilled in the art as a "double seam"—a seam composed of five folds or thicknesses. It will be understood, however, that our invention may be practiced with or applied to folded seams having a greater or less number of folds or thicknesses.

In the drawings, Figure 1 is a side elevation of a can or vessel embodying our inven-

tion. Fig. 2 is an enlarged detail cross-section through the folded seam. Fig. 3 shows the ordinary form of seam prior to being longitudinally grooved according to our invention. Fig. 4 is an enlarged sectional view illustrating the grooving step or operation and showing the chuck or head for supporting the inner side or wall of the seam and the grooving-roller for forming the groove in the outside of the seam. Fig. 5 is a detail view showing the form of the seaming-flanges on the can-body and can-head before the double or other seam is formed. Fig. 6 shows the first step of the folding operation in forming the double seam; and Figs. 7, 8, 9, and 10 show the longitudinal groove formed in different positions on the outside of the seam, the latter (Fig. 10) showing the seam provided with two longitudinal grooves instead of one.

In the drawings, *a* represents the can-head, *b* its countersink or upright flange, and *d* its seaming-flange.

c represents the can-body, and *e* its seaming-flange, the same being shorter and narrower than the seaming-flange *d* on the head *a*, so that said flange *d* may fold over the flange *e*.

In practicing our invention the seaming-flanges *d* and *e* of the can-head and can-body are first bent, folded, rolled, or formed into a folded seam *F*, preferably a double seam, substantially as illustrated in Fig. 3, and having a series of three or more, preferably five, folds, layers, or thicknesses, 1, 2, 3, 4, and 5, counting from the outside to the inside, the seam being formed in the usual way by a set of two or more successively-operating and suitably-shaped double-seaming rollers acting in conjunction with a chuck or head, as *N*, which fits inside the countersink of the can-head. The seaming-rollers operate to curl or fold the projecting portion of the seaming-flange *d* of the can-head over and around the seaming-flange *e* on the can-body and to bend the two down against the exterior wall of the can-body. After the seam *F* is thus formed or simultaneously with its finishing one side thereof, preferably its outside, is provided with a longitudinal groove *f*, extending the length of the seam or around the can, this being done by a narrow bead or rib *m* on the finishing-roller *M* of the seaming mechanism in connection with the chuck or head *N*, which fits inside of the countersink of the can-head and supports and maintains in its original smooth shape the innermost fold or wall 5 of the seam *F*, while the outermost folds 1 2 are longitudinally grooved by the action of the bead or rib *m* of the seaming-roller *M*. The rib or bead *m* may be provided on the final or finishing roller of the ordinary set of double-seaming rollers heretofore in use, or an extra seaming-roller provided with such head or rib *m* may be employed as the ribbed or beaded roller *M*, if desired. The longitudinal groove *f* in

the outer folds of the seam may preferably be centrally located in respect to the width of the seam as a whole, as illustrated in Fig. 2, 70 though its position on the seam may be varied without departing from our invention, as will be readily understood from the drawings Figs. 7, 8, 9, and 10.

The longitudinal groove *f*, formed in one 75 side of the seam and extending in or through one or more of its folds 1 2, while one or more of the folds 5 4 of the seam on the opposite side thereof are maintained in their original plain smooth shape during the grooving operation has the effect to materially reduce the thickness of the seam as a whole along the line of its longitudinal groove and to force 80 into the most close intimate metal-to-metal contact the superimposed surfaces of the several folds or layers 1, 2, 3, 4, and 5 of the seam and to effectually close up the most minute or hair-like crevices or passages that would otherwise be left, and thus to make the seam perfectly secure and hermetically tight. 90

It will be understood that the operation and effect of the grooving-roller *M*, having the bead or rib *m* in conjunction with the supporting chuck or head *N* on the opposite side of the seam which resists the thrust of the bead 95 of the grooving-roller, is to compress and compact the seam and reduce its thickness as a whole along the line of the groove and not simply to form a corrugation, groove, or bend extending through all the thicknesses of the 100 seam from one side thereof to the other, as would be the case if one or more folds of the seam were not supported and maintained in their original shape during the grooving operation, and thus prevented from yielding under 105 action of the annular rib or bead *m* of the grooving-roller *M*.

We have used the term "folds" as indicating the several superposed layers or thicknesses of the seam, and this applies whether the seam is of a roll type and substantially circular in cross-section (except for the groove *f*) or more or less oblong in cross-section, as shown in the drawings.

In our invention the external grooving operation has or may have the effect to thin or reduce the thickness of the outer folds or layers of the seam along the line of the external longitudinal groove *f*; but this is attended with no injury, as the groove gives the 120 seam a stronger form. The longitudinal groove *f* also gives the seam and the can as a whole a neat finish.

As in our invention the inside face or wall of the seam has no indentation, groove, projection, or corrugation therein, but is smooth and plain, the external grooving operation of course does not lock the can to the chuck-head, as would be the case if the same were indented, grooved, or corrugated on both its 130 inside and outside faces and it were attempted to so indent, groove, or corrugate it from the outside while supported on the inside by the chuck-head, as done in our invention.

One important advantage of our improved can is thus: its great simplicity and cheapness of manufacture and its adaptability to be made by the ordinary double-seaming mechanisms or machines now in general use by the simple addition of a grooving head or rib to the finishing-roller of the seat of double-seaming rollers or by adding an extra seaming-roller having such bead or rib to the set of double-seaming rollers now in use.

Having thus fully described our invention, what we claim as new, and desire to secure by Letters Patent, is—

1. A sheet-metal can comprising a head and body, and a solderless folded seam uniting the same, said seam having a longitudinal groove in one outer or exposed side thereof extending the length of the seam around the can, and a plain smooth wall on its opposite outer or exposed side, substantially as described.

2. In a sheet-metal vessel, a solderless folded seam comprising three or more folds or thicknesses and having in the outer thickness on one side of said seam a longitudinal groove and the outer thickness on the other side of said seam plain or smooth, substantially as described.

3. A sheet-metal vessel comprising a head and body and a solderless seam uniting the same, said seam having two or more longitudinally and correspondingly grooved folds on one side thereof and two or more plain smooth folds on the opposite side thereof, substantially as described. 30

4. A sheet-metal vessel having a solderless seam comprising two or more longitudinally and correspondingly grooved folds on one side of the seam, and two or more plain smooth folds on the opposite side of the seam, substantially as described. 40

5. A sheet-metal vessel having a solderless seam composed of three or more superimposed folds, two or more of which on one side of the seam have a longitudinal groove and the other or others of which are plain and smooth, substantially as described. 45

In testimony that we claim the foregoing we have hereunto set our hands this 20th day of March, 1903.
